UNITED STATES PATENT OFFICE.

JOHN T. HARPER, OF LEOTI, KANSAS.

LACE EYELET.

Application filed July 20, 1921. Serial No. 486,151.

To all whom it may concern:

Be it known that I, JOHN T. HARPER, a citizen of the United States, residing at Leoti, in the county of Wichita and State of Kansas, have invented certain new and useful Improvements in Lace Eyelets; and I do hereby declare the following to be a full, clear, and exact description of the invention, such as will enable others skilled in the art 10 to which it appertains to make and use the same.

The object is to provide a simple and readily applicable lacing eyelet for shoes and other garments which will provide for a 15 uniform tensioning of the lacing, a free running movement thereof and a proper positioning of the edges of the garment relative to each other, which can be constructed at a small cost and applied to the garment without special preparation of the latter and which will adapt itself to strains applied to the lacing so as to insure comfort to the wearer of the garment, and with these objects in view, the invention consists in a construction and combination of parts of which a preferred embodiment is shown in the accompanying drawings, wherein:—

Figure 1 is a view of a shoe equipped with lacing eyelets embodying the invention,

30 Figure 2 is a detail edge view of one of the eyelets showing the edge of a garment in section,

Figure 3 is a detail view of one of the eyelets detached, the ends of the same being interlocked,

35 Figure 4 is a similar view with the ends of the eyelets separated as they appear prior to the last step in the formation of the eyelet,

Figure 5 is a view of the blank from which the eyelet is formed and showing the same as it may be stamped from a sheet of metal or other suitable material, and

40 Figure 6 is a detail view of the completed eyelet, illustrating the relative position of its parts before it is applied to a garment, a portion of the outer side member of the eyelet being in longitudinal section.

The eyelet consists of a loop of which the 45 side members 10 and 11 respectively carry interlocking complementary means such as the eye 12 and the tongue 13, the latter being struck from the arm or side 11 of the loop and as originally formed lying within the 50 contour and area thereof and being separated throughout its length from the remaining

portion of said side or arm by the cut away portion 14.

In applying the eyelet to the garment, the 60 tongue which is preferably reduced substantially to a point is deflected inwardly at right angles to the plane of the arm or side 11 of the loop and after passing through the edge portion of the garment shown at 15 is passed through the eye 12 and then bent rearwardly or away from the loop as shown at 18^a to clamp the eye carrying end of the 65 side or arm 10 in contact with the surface of the garment.

This method of mounting permits of a 70 swinging movement of the eyelet in the plane of the garment to adapt itself to the direction of strain applied thereto by the lacing 17, and as applied to shoes an eyelet in addition being arranged at each side of the opening of the vamp or upper may be 75 arranged at the lower end of said opening where the side edges of the upper come together or intersect as shown at 18 to receive the loop of the lace.

The eyelets permit of the free sliding 80 movement of the lace therethrough and to facilitate this movement the looped ends thereof are preferably rounded as indicated at 19 to avoid contact of the edges with the lace and therefore the chafing which might result therefrom.

Obviously the eyelet may be attached to 85 the garment merely by passing the tongue through the latter and the eye of the other arm or side of the loop and then crimping or pressing the end of the tongue back as above described, and hence practically in a single operation, and if the device is used in connection with shoes already provided with the ordinary forms of eyelets, the latter may be utilized as the openings through which the tongues are passed, so that the device is adapted to be used as an attachment to shoes 90 already in use or already provided with lacing eyelets of the ordinary form.

Furthermore, it will be obvious that the 95 eyelets as described may be rendered practically inconspicuous by coloring the same to agree with that of the leather or other material forming the garment, or may be made decorative or attractive in design and appearance to suit the preference of the manufacturer or the trade.

Having thus described my invention what 100 I claim is:—

A lacing eyelet consisting of a blank

formed into substantially parallel spaced arms, one of the arms adjacent its free end having a slot therethrough, the other arm opposite said slot being reduced in width, a 5 relatively narrow tongue extending from the reduced portion and adapted for passage through said slot, that portion of the tongue lying between said reduced portion and slot when the eyelet is fastened in position being disposed through an article to 10 secure the eyelet in place, the lace being disposable intermediate said arm and said

tongue and the bridge connecting the arm, the lace being adapted to directly contact with the inner surface of said bridge, and 15 said bridge being curved whereby its inner surface will be convexed.

In testimony whereof I affix my signature in presence of two witnesses.

JOHN T. HARPER.
